UNITED STATES PATENT OFFICE.

LEWIS S. STODDARD AND BERTHOLD GOLDSMITH, OF LISBON, OHIO.

APPARATUS FOR COATING SHEET, PLATE, AND ROLLED METAL.

1,142,856.

Specification of Letters Patent. Patented June 15, 1915.

Application filed July 21, 1914. Serial No. 852,277.

To all whom it may concern:

Be it known that we, LEWIS S. STODDARD and BERTHOLD GOLDSMITH, both residents of Lisbon, in the county of Columbiana and

5 State of Ohio, have invented a new and useful Improvement in Apparatus for Coating Sheet, Plate, and Rolled Metal, of which the following is a specification.

This invention relates to apparatus for 10 coating roll, sheet and plate metals or alloys, with a coating of metals or alloys, and more particularly to apparatus for coating such metals or alloys on one surface only.

The object of the invention is to provide 15 for this purpose an apparatus of simple construction, whereby roll, sheet or plate metals or alloys can be rapidly and thoroughly coated with a substantially uniform layer of the coating metals or alloys, and whereby 20 the coating material is prevented from being deposited on the edges and the opposite surface of the metals or alloys being coated,— and also prevented from being wasted through excessive oxidation and otherwise.

25 The invention comprises the construction and arrangement of apparatus hereinafter described and claimed.

In the accompanying drawings, Figure 1 is a plan view of the apparatus; Fig. 2 is a 30 side elevation of the same; Fig. 3 is a vertical cross section thereof on the line 3—3, Fig. 2; Fig. 4 is a vertical longitudinal section on the line 4—4, Fig. 1 through the melting and depositing or distributing tank 35 or pot; and Fig. 5 is a detail view of an edge wiper.

In the drawings, 1 illustrates a suitable frame of any adaptable construction or material upon which the operating parts are 40 mounted. Mounted on one end of this table or frame are one or more suitable spools or drums 2 upon which is placed a coil or roll of the metal to be coated, when roll metal is used.

45 3 represents a fluxing pan or tank, preferably a lead pan, for containing the fluxing material, such as chlorid of zinc. Mounted in frame 1 to revolve under pan 3 is a fluxing roll 4, this preferably being covered with 50 cotton, or other suitable soft material for depositing flux on the upper side of the roll, sheet or plate, the latter being represented by the line 5. The fluxing pan or tank 3 is provided in its bottom with suitable perforations through which the fluxing material

drips and is carried by the roll 4 and deposited on the upper surface of the metal 5 passing under roll 4. The sheet or plate 5 is held in contact with said fluxing rolls by means of two idler rolls 6, one on each side 60 of the roll 4 and over which the sheet or roll passes. By this arrangement the upper surface of the plate, sheet or roll metal or alloy is thoroughly fluxed. The plate, sheet or roll metal then passes underneath one or more 65 distributing and absorbing pads 7 which preferably are constructed of wood or metal covered with a fibrous substance, such as cotton cloth. These pads distribute flux evenly over the upper surface of the plate, sheet or 70 roll metal, and also absorb any surplus flux which may have been deposited thereon by the fluxing roll. Preferably, the fluxing roll 4 is rotated by its frictional contact with the plate, sheet or roll metal passing thereunder, 75 but if desired it can be positively driven, such as by means of a suitable sprocket chain, belt or the like 8 connecting a wheel 9 on the end of said roller shaft with a similar wheel or pulley 10 on a suitable driving shaft 80 11. The sheet then passes under a depositing or distributing pot or tank 12 containing the molten coating metal or alloy. The pot or tank 12 is supplied with the molten coating metal or alloy from a suitable melting 85 pot or tank 13 which may be heated in any suitable way, such as by means of a gas or oil burner, or by setting the same into a suitable stove or furnace 14, as shown, in which a fire of any character is maintained, 90 in order to keep the coating metal or alloy in a suitable fluid condition. The molten metal or alloy is transferred from the melting pot or tank 13 to the depositing or distributing pot or tank 12 by means of two 95 vertical reciprocating plunger lifters, each of which comprise a suitable tube 15 dipping down into the tank 13 and in which reciprocates a suitable valved head 16 which may be of any pump head construction capable when 100 the head is depressed of allowing molten metal or alloy to pass through said head, and when said head is lifted to close and lift the molten metal which has passed there-through, and be lifted thereby and discharged through an opening 17 in the tube or barrel 15 into the depositing or distributing tank 12. The lifting heads 16 are alternately reciprocated vertically by any suitable means, that shown comprising rods 18 con- 110

nected to said heads and being jointed to straps 19 operating upon eccentrics or cams 20 secured to the driving shafts 11.

By having two plunger lifts, one on each side of the apparatus, a steady supply of molten metal or alloy is supplied to the depositing and distributing tank 12. The latter is sealed tight by a suitable cover, but is provided in its bottom 21 with a slot or opening 22 through which the molten metal or alloy is discharged upon the upper surface of the sheet or roll of metal passing underneath the tank or pot. This slot is preferably controlled by means of a suitable valve, which may be of various constructions, and which is shown as a wedge shaped bar 23 provided at its ends with swiveled connections to threaded rods 24 projecting from the end of the tank 12 and which rods are provided with suitable rotating members, such as the handles 25.

Beyond the distributing or depositing tank 12, along the path of movement of the sheet are one or more stripping devices, such as brushes or the rods 26 shown, which are so located as to drag against the upper surface of the sheet of metal passing thereunder, and which serve to distribute the coating metal or alloy over the sheet or plate and also remove a considerable portion of the surplus coating metal or alloy, which removed portion drops back into the melting pot or tank 13. The sheet or plate then passes underneath and in contact with one or more rotary wipers or brushes 27, two such brushes being shown. These are in the form of rolls and are covered by a suitable yielding wiping material, preferably tow, although the covering may be of other fibrous material. The sheet or plate is held in contact with these wiping brushes by means of idler rolls 28, three such rolls being shown mounted in the frame 1 and bearing against the under surface of the sheet or plate. The brushes 27 are positively rotated in the direction of the arrows 29, that is, in a direction contrary to the direction of travel of the sheet or plate, and therefore serve to wipe off the surplus coating material and finish the upper coated surface of the sheet or plate. These rolls may be rotated by any suitable mechanism, such as by being connected together by the sprocket chain, belt or similar driving member 30 so as to rotate in unison, and one thereof being driven by means of a suitable sprocket chain, belt or the like 31 from the driving shaft 11.

In conjunction with each of the wiping rolls is provided a scraper and guard, in the form of a curved plate 33 attached to the frame or table 1, and having a trough-shaped scraping edge 34 serving to scrape from the wiping rolls any coating material which may adhere thereto and conduct it to

the sides of the machine, and also serving as a guard to prevent such coating material from being thrown against the coated surface of the sheet or plate.

To prevent the coating metal from being deposited on the edges of the sheet or plate we provide suitable edge wipers 39, which are in the form of small rolls on a shaft 40 mounted on the frame or table 1 below the sheet or plate 5, and suitably driven at the desired speed by suitable means, such as the sprocket chain, belt or the like 41 connecting the same to the shaft of one of the wiping rolls. The rolls 39 are preferably formed of wood covered with a suitable textile material, such as canton flannel or the like, and bear against the edges of the sheet or plate 5 and wipe off any coating material which may have run onto the same.

Any suitable mechanism may be used for drawing the roll, sheet or plate metal through the apparatus described. As illustrated, this is effected by means of a spool or drum 35 rotatably mounted in suitable bearings on the table or frame 1, and upon which the plate, sheet or roll metal is wound, and which spool or drum can be driven in any suitable way, such for instance as by means of the sprocket chain, belt or similar member 36 connecting said spool or drum 35 with one of the wiping rolls 27, the latter being driven, as before stated, from the driving shaft 10. The driving mechanism for the various rolls on the spool or drum may be arranged in any desired or preferred way, and the particular arrangement shown in the drawings is merely one arrangement suitable for this purpose. Power can be supplied to the driving shaft 10 from any suitable source, such as by means of a belt 38 coming from any power shaft and running over fast and loose pulleys 39 on the driving shaft 10. The driving mechanism is arranged to rotate the various rolls in the directions indicated by the arrows and at the necessary speeds.

The apparatus described is of simple construction and is so arranged as to quickly, thoroughly and uniformly coat the plate, sheet or roll metal. Surplus coating material is scraped and wiped off so as to give a practically uniform coating, and the edges and under surface of the sheet or plate metal are kept reasonably clean from the coating metal. The operation of the apparatus described will be readily understood from the foregoing description.

What we claim is:—

1. Apparatus for coating plate, sheet or rolled metal, comprising a melting pot or tank for the coating metal or alloy, a depositing and distributing pot or tank located above the course of the sheet or plate to be coated, and means for lifting the molten coating material from the melting pot or

- tank to the depositing and distributing pot or tank.
2. Apparatus for coating plate, sheet or rolled metal, comprising a melting pot or tank for the coating metal or alloy, a depositing and distributing pot or tank located above the course of the sheet or plate to be coated, and vertical reciprocating plunger lifts for lifting the coating material from the melting pot or tank to the depositing and distributing pot or tank.
3. Apparatus for coating plate, sheet or rolled metal, comprising a melting pot or tank for the coating metal or alloy, a depositing and distributing pot or tank located above the course of the sheet or plate to be coated, a pair of reciprocating plunger lifts for transferring the coating material from the melting pot or tank to the depositing pot or tank, and means for actuating said reciprocating lifts alternately.
4. Apparatus for coating plate, sheet or rolled metal or alloys, comprising a distributing or depositing pot or tank provided in its bottom with a valve controlled discharge orifice, means for drawing the metal to be coated underneath said pot or tank, in combination with fluxing means and wiping means.
5. Apparatus for coating plate, sheet or rolled metal or alloys, comprising a sealed distributing or depositing tank provided in its bottom with a discharge opening, means for supplying molten coating material to said pot or tank, means for drawing the metal to be coated underneath said pot or tank, in combination with fluxing means in advance of said pot or tank, and wiping means in the rear of said pot or tank.
6. Apparatus for coating rolled, sheet or plate metal or alloys, comprising a distributing and depositing pot or tank arranged to discharge the coating material on the upper surface of the sheet or plate, means for drawing said sheet or plate underneath said pot or tank, scraping and wiping means to the rear of said pot or tank arranged to contact with the upper surface of the coated sheet or plate, and wipers engaging the edges of said sheet or plate.
7. Apparatus for coating rolled, sheet or plate metal or alloys, comprising a distributing and depositing pot or tank arranged to discharge the coating material on the upper surface of the sheet or plate, means for drawing said sheet or plate underneath said pot or tank, scraping and wiping means to the rear of said pot or tank arranged to contact with the upper surface of the coated sheet or plate, and wiping rolls engaging the edges of said sheet or plate.

In testimony whereof, we have hereunto set our hands.

LEWIS S. STODDARD.
BERTHOLD GOLDSMITH.
